UNITED STATES PATENT OFFICE.

HANS R. SETZ, OF DE HODIAMONT, MISSOURI, ASSIGNOR TO FULTON IRON WORKS, OF DE HODIAMONT, MISSOURI, A CORPORATION OF MISSOURI.

VARIABLE-FEED PUMP.

1,188,331.

Specification of Letters Patent. Patented June 20, 1916.

Application filed July 26, 1915. Serial No. 42,065.

To all whom it may concern:

Be it known that I, HANS R. SETZ, a citizen of the United States, residing at De Hodiamont, St. Louis county, Missouri, have invented a certain new and useful Improvement in Variable-Feed Pumps, of which the following is a full, clear, and exact description, such as will enable others skilled in the art to which it appertains to make 10 and use the same.

This invention relates to variable feed pumps of the type described in the pending applications of George D. Pogue, for variable feed pumps, Serial No. 967, filed January 7, 15 1915, and Serial No. 40678, filed July 19, 1915, in which the plunger-operating mechanism consists of a fixed-stroke actuating member, a variable-stroke member and an interposed connecting device that is adapted 20 to be tripped or rendered inoperative at different periods in the cycle of operations of the pump, so as to vary the supply from the pump.

The main object of my invention is to provide 25 a pump that embodies all of the good features and characteristics of the pump described in said Pogue applications, but which is so designed that the fixed-stroke actuating member acts directly upon one 30 end of the variable-stroke member during the displacement stroke of the pump piston.

Another object is to provide a pump of the type mentioned, in which the plunger-operating mechanism is composed of only 35 a few parts of simple design that can be made large and strong enough to successfully withstand the strains to which they are subjected when the pump is in service.

Another object is to provide a variable 40 feed pump of the type mentioned, in which the plunger-operating mechanism is strong, inexpensive to manufacture and capable of being adjusted easily to compensate for wear. And still another object is to provide 45 a variable feed pump of the type mentioned, which comprises a novel means for rendering the plungers of the pump inoperative without stopping the propelling or driving mechanism of the pump.

50 Other objects and desirable features of my invention will be hereinafter pointed out.

Figure 1 of the drawings is a vertical transverse-sectional view of a variable feed

pump constructed in accordance with my 55 invention. Fig. 1^a is a detail view, illustrating one of the adjustable rock arms that is employed for moving the tripping blocks that coöperate with the connecting elements of the plunger-operating mechanism, and 60 Fig. 2 is a front elevational view, partly broken away, of the pump shown in Fig. 1.

In the pump herein shown, which represents the preferred form of my invention, the connecting element of each plunger-operating mechanism is tripped automatically, sooner or later, on the suction stroke of the plunger, so as to regulate the supply from the cylinder with which the plunger coöperates, but it is immaterial, so far as certain features of my invention are concerned, whether said connecting element is tripped on the suction stroke of the pump plunger or on the displacement stroke of said plunger.

As shown in the drawings, the pump is 75 provided with a plurality of plungers A, each of which reciprocates in a cylinder B that is equipped with an inlet valve 1 and one or more discharge valves 2. A separate and distinct operating mechanism is provided for each plunger and all of said plunger-operating mechanisms are propelled or actuated from a single crank shaft C, driven by some suitable means (not shown) and provided with crank arms that are connected by means of links 3 with the fixed-stroke actuating members of the plunger-operating mechanisms, said crank shaft being arranged in a housing 4 that is adapted to hold oil.

90 Each plunger-operating mechanism consists of a fixed-stroke actuating member D, a variable-stroke member E and a connecting element or device F that transmits movement from the fixed-stroke member to the variable-stroke member on the suction stroke of the pump plunger, the members D and E being so designed and arranged that the fixed-stroke member D will act directly upon the variable-stroke member E during 95 the displacement stroke of the plunger. The fixed-stroke member D is provided at its lower end with a bifurcated portion and the connecting element F is pivotally mounted in said bifurcated portion at one side of 100 the longitudinal axis of the member D. The connecting element F is pivotally mounted 105 at the other side of the longitudinal axis of the member D.

The variable-stroke member E preferably consists of an extension on the pump plun-

ger B, and said member E extends upwardly through the bifurcated portion of the member D at one side of the connecting element F, the upper end portion 5 of the variable-stroke member E projecting into a socket or guideway in the fixed-stroke member D, as shown clearly in Fig. 1. The connecting element F coöperates with a shoulder on the variable-stroke member E, which is preferably formed by a block 6 that is arranged below the guiding portion 5 at the upper end of the member E, said block coöperating with the side parts of the bifurcated portion of the actuating member D, to prevent the variable-stroke member from turning. The upper end of the connecting element F is normally held in engagement with the shoulder 6 on the member E by means of a spring 7 on the member D, as shown in Fig. 1, and said connecting element is provided at its lower end with a roll 8 that co-
operates with a tripping device at a certain period in the cycle of operations of the pump, as hereinafter described.

One desirable feature of a plunger-operating mechanism of the construction above described is that the fixed-stroke actuating member D bears directly upon the upper end of the variable-stroke member E and exerts a direct thrust on the variable-stroke member, during the displacement stroke of the pump plunger, thereby reducing to a minimum the liability of the plunger-operating mechanism getting out of order on account of any parts of same breaking.

The members D and E consist of two rugged parts that can be manufactured cheaply by simple machine operations; and still another desirable feature of such a construction is that the fixed-stroke member acts as a guide for the variable-stroke member and prevents said variable-stroke member from turning or moving out of longitudinal alignment with the parts that move same. If the shoulder on the variable-stroke member with which the connecting element F coöperates becomes worn, the member E can be removed from the member D and given a quarter turn, so as to bring a different surface on the block 6 into operative position with relation to the connecting element F. Such a construction also makes it possible to keep the coöperating parts of the plunger-operating mechanism thoroughly lubricated, when the pump is in operation, this being effected by forming a lubricating duct 9 in the member D, as shown in full lines in Fig. 1, and a lubricating duct 10 in the member E, as shown in dotted lines in Fig. 1. After the variable-stroke member E has come to rest, during the suction stroke of the actuating member D, the partial vacuum that is created in the upper end portion of the socket in the member D, in which the guiding portion 5 of the variable-stroke

member is arranged, causes oil to be sucked out of the housing 4 through the duct 9 that establishes communication between said housing and said socket. On the succeeding displacement stroke of the actuating member D the surplus oil in said socket will be forced back into the housing through the oil duct 9, but a thin film of oil will remain between the upper end of the guiding portion 5 on the variable-stroke member and the end wall of the socket, and thus partially reduce the impact between said surfaces and also prevent said surfaces from wearing rapidly. Some of the oil also leaks downwardly through the duct 10 in the variable-stroke member and escapes laterally through the branches at the lower end of the duct to the outer surfaces of the variable-stroke member D on which the connecting element F normally bears, thereby preventing excessive wear on these coöperating surfaces.

The mechanism for governing the supply from the pump consists of a plurality of tripping devices that trip the connecting elements F or cause said elements to be rendered inoperative sooner or later on the suction stroke of the plunger-operating mechanism. A tripping device is provided for the plunger-operating mechanism of each cylinder and all of said tripping devices are under the control of an automatic governing device and also a manually-operated means that is of novel construction and so designed that it is possible to cut all of the cylinders of the pump out of service without affecting the operation of the actuating members D of the plunger-operating mechanisms.

In the pump herein shown the tripping devices, previously referred to, consist of sliding blocks G that coöperate with friction rolls 8 on the connecting elements F in such a manner that each of said connecting elements F will be disengaged from its co-operating variable-stroke member before the fixed-stroke member D that carries said connecting element reaches its upper limit of movement. Each of said blocks has a flat surface α that lies parallel to the axis of the fixed-stroke member D and also an inclined or oblique surface γ , as shown in Fig. 1, the position of said surfaces being such that the friction roll 8 on each of the connecting elements F will travel over the inclined surface γ of its coöperating tripping block and then onto the surface α on said block, during the upward stroke of the actuating member D, thereby causing said connecting element F to be automatically tripped or disengaged from the variable-stroke member with which it coöperates. The tripping blocks G are moved automatically by means of arms or levers 11 on a governor-controlled rock shaft H, which is

operatively connected with the automatic governor of the engine in such a manner that the position of said shaft H will change when the collar I of the governor moves up 5 and down, owing to variations in the speed of the engine, the means herein illustrated for transmitting movement from the governor collar I to the rock shaft H consisting of an arm 12 on said rock shaft and a 10 rod 13 that co-operates with a yoke-shaped rock arm 14 which is connected to the governor collar by means of links 15, as shown in Fig. 1.

In order that the relative amount of fuel 15 supplied by any cylinder of the pump may be increased or decreased, I have connected the arms 11 to the rock shaft H in such a manner that said arms can be adjusted relatively to said rock shaft. One convenient 20 way of accomplishing this is to provide the rock shaft H with a rigid hub 11^a for each of the arms 11 and equip said hub with two adjusting screws 11^b and 11^c, as shown in Fig. 1^a that bear against shoulders on said 25 arms. By manipulating the screws 11^b and 11^c the position of the arms 11 can be changed easily, so as to vary the position of the tripping blocks with relation to the governor-controlled shaft H that operates the 30 levers 11.

In order to facilitate the adjustment of the arms or levers 11, I have provided each of the stationary hubs 11^a on the shaft H with a pointer 16, as shown in Fig. 2, that 35 co-operates with graduations 17 on the hub portion of the particular lever with which it co-operates. The rod 13 that connects the shaft H with the rock arm 14 passes freely through a guide wing 14^a on the hub of the 40 rock arm 14 and is normally held in fixed relation with said rock arm by means of a nut 19 on the rod 13 that bears against the upper side of the wing 14^a, and a spring 20 that is arranged between the underside of 45 said wing and a stop 21 on the lower end of the rod 13, as shown in Fig. 1, said spring 20 being strong enough so that it will not give or yield when the arm 14 is rocked by the movement of the governor collar I. If 50 it is desired to cut all of the pump cylinders out of service while the fixed-stroke members of the plunger-operating mechanisms continue in operation, the rod 13 is moved upwardly, so as to arrange the nut 19 thereon 55 in such a position that it will not be engaged by the wing 14^a on the rock arm 14 when said rock arm is moved upwardly by the governor collar, it, of course, being understood that the upward movement of the 60 rod 13 causes the shaft H to be rocked into such a position that the tripping blocks G engage the connecting elements F of the plunger-operating mechanisms and hold 65 said connecting elements in an operative position. One means that may be employed

for moving the rod 13 upwardly so as to render said rod inoperative with relation to the governor-controlled rock arm 14, consists of a manually-operated lever 22, shown in Fig. 2, which is provided with a bifurcated end that straddles the rod 13 and engages a shoulder 23 thereon when the free end of said lever is depressed, said lever 22 being provided with any suitable means for locking it in its depressed position, the 70 means herein shown for this purpose consisting of a pin 24 in the lever that is adapted to enter an opening 25 in a stationary plate 26 arranged in proximity to the handle of the lever. A means of the construction 80 above described for actuating the tripping blocks G is of such simple design that it is not apt to get out of order; it is inexpensive to manufacture; it enables the arms 11 that actuate the tripping blocks to be adjusted 85 accurately with relation to the governor-controlled shaft on which the arms are mounted and it enables all of the connecting elements of the plunger-operating mechanisms to be rendered inoperative simultaneously. 90

In order that one or more cylinders of the pump may be cut out of service without affecting the operation of the other cylinders, I have provided each cylinder with a 95 manually-operated cut-off valve 27, shown in Fig. 1, that is adapted to be moved into position to close the inlet pipe 28 to the cylinder, the stem of said valve having a screw-threaded portion so as to enable said valve to be closed and opened by rotating the stem of the valve which projects outwardly through a stuffing box 29. If desired, each cylinder of the pump may be provided with a manually-operable priming 100 plunger 30 for drawing the liquid into the cylinder of the pump to prime same, said plunger being normally locked in an inoperative position by means of a wing nut 31 that is mounted on a screw-threaded portion 105 on the stem of the plunger, as shown in Fig. 1. When said wing nut is loosened or backed away from the stuffing box through which the stem of the plunger projects, the plunger 30 can be operated manually so as 110 to draw the liquid from the supply pipe 28 through the inlet valve into the cylinder of the pump. 115

It is immaterial, so far as my broad idea is concerned, how the frame or body of the 120 pump is formed, but I prefer to form each pump cylinder and its co-operating valves as a separate unit that is detachably connected to the frame of the pump in which the plunger-operating mechanism is mounted. As shown in Figs. 1 and 2, the frame 125 32, in which the fixed-stroke actuating members and the tripping blocks are mounted, is provided with a bottom cross piece 33 that is arranged under the portion of the frame in 130

which the actuating members D are guided. Each pump cylinder B is formed in a separate casting 34 and all of said castings are detachably connected to said cross piece 33, from which they depend, as shown in Fig. 5. One convenient way of connecting the pump cylinder castings 34 to the frame of the pump is illustrated in Fig. 2, wherein 35 designates a reduced cylindrical extension 10 on the upper end of the casting that projects upwardly through the cross piece 33 and which is provided with external screw-threads onto which a clamping nut 36 is screwed. By forming the pump body in this manner I reduce the cost of manufacture, facilitate repairs and enable the pump to be modified easily to adapt it to varying conditions.

Having thus described my invention, 20 what I claim, and desire to secure by Letters Patent, is:

1. A variable feed pump provided with a plunger-operating mechanism that comprises a fixed-stroke actuating member, a 25 variable-stroke member arranged so that the actuating member will bear on one end of same when said actuating member moves in one direction, a connecting element for transmitting movement from the actuating member to the variable-stroke member when said actuating member moves in the opposite direction, and coöperating guiding portions of said members arranged intermediate the connecting element and the end of 30 said variable-stroke member for preventing said variable-stroke member from turning.

2. A variable feed pump provided with a plunger-operating mechanism that comprises a fixed-stroke actuating member, a 35 variable-stroke member, a tripable connecting element arranged intermediate the ends of said variable-stroke member for transmitting movement from the actuating member to the variable-stroke member when said actuating member moves in one direction, and a rigid extension on said variable-stroke member that projects beyond said connecting element and whose end is engaged by 40 said actuating member when the latter moves in the opposite direction.

3. A variable feed pump provided with a plunger-operating mechanism that comprises a fixed-stroke actuating member, a 45 variable-stroke member, a connecting element carried by said actuating member and adapted to engage a shoulder on said variable-stroke member, said actuating member having a socket, and an end portion on said variable-stroke member arranged beyond the shoulder thereon and projecting 50 into the socket in said actuating member.

4. A variable feed pump provided with a plunger-operating mechanism that comprises a fixed-stroke actuating member, a 55 variable-stroke member that is guided by

said actuating member, and a connecting element carried by said actuating member and adapted to engage a shoulder on said variable-stroke member located intermediate the ends of same, said variable-stroke member having a portion projecting beyond said shoulder which is engaged by the fixed-stroke member when the latter moves in one direction.

5. A variable feed pump provided with 75 a plunger-operating mechanism that comprises a fixed-stroke actuating member provided with a socket, a variable-stroke member provided with a solid shank that projects into said socket and bears against the bottom of same when said actuating member moves in one direction, and a movable connecting element on said actuating member arranged adjacent the free end of same and at a point beyond the shank on said 80 variable-stroke member.

6. A variable feed pump provided with a plunger-operating mechanism that comprises a fixed-stroke actuating member provided at its lower end with a bifurcated portion, a variable-stroke member provided with a part that slides between the parallel walls of said bifurcated portion, a rigid extension on said variable-stroke member that projects into a socket in said actuating member that is located beyond the bifurcated portion of said member, and a tripable connecting element in said bifurcated portion arranged at one side of the longitudinal axis of said variable-stroke member 100 and adapted to engage and move same.

7. A variable feed pump provided with a plunger-operating mechanism that comprises a fixed-stroke actuating member, a variable-stroke member integrally connected 105 to the pump plunger and provided with an end portion that fits in an opening in said actuating member, and a shoulder on said variable-stroke member arranged intermediate the ends of same and adapted to co-operate with a tripable connecting element on the actuating member.

8. A variable feed pump provided with a plunger-operating mechanism that comprises a variable-stroke member that is attached to the pump plunger, a fixed-stroke actuating member that exerts a direct thrust on the end of said variable-stroke member when said actuating member moves in one direction, and a movable means arranged intermediate the ends of said variable-stroke member for coupling said members together on the reverse stroke of said actuating member.

9. A variable feed pump provided with 125 a plunger-operating mechanism that comprises a fixed-stroke actuating member, a variable-stroke member, a tripable connecting element on said actuating member, and a portion on said variable-stroke member 130

provided with a plurality of shoulders, each of which can be brought into operative position with relation to said connecting element by changing the position of said variable-stroke member.

10. A variable feed pump provided with a plunger-operating mechanism that comprises a variable-stroke member, a fixed-stroke actuating member that exerts a thrust on the end of said variable-stroke member when said actuating member moves in one direction, and means for causing a film of oil to be supplied to the end face of said variable-stroke member and to the surface 15 of said actuating member that co-operates with said end face.

11. A variable feed pump provided with a plunger-operating mechanism that comprises a fixed-stroke actuating member provided with a socket, a variable-stroke member having a portion that projects into said socket, and means for causing a lubricating medium to be supplied to said socket so as to form a film of oil between the variable-stroke member and the end wall of said socket that bears against same when the actuating member moves in one direction.

12. A variable feed pump provided with a plunger-operating mechanism that comprises a crank shaft, an oil housing that incases said crank shaft, a fixed-stroke actuating member operated by said crank shaft, said actuating member having a socket, a variable-stroke member having a portion that projects into said socket, and an oil duct in said actuating member that establishes communication between the socket therein and said oil housing.

13. A variable feed pump provided with a plunger-operating mechanism that comprises a crank shaft, an oil housing that incases said crank shaft, a fixed-stroke actuating member operated by said crank shaft, said actuating member having a socket, a variable-stroke member having a portion that projects into said socket, an oil duct in said actuating member that establishes communication between the socket therein and said oil housing, a tripable connecting element on said actuating member that co-operates with said variable-stroke member, and means for supplying lubricating oil to the outer surface of said variable-stroke member.

14. A variable feed pump provided with a plunger-operating mechanism comprising a fixed-stroke actuating member that is provided with a socket, a variable-stroke member having a portion that projects into said socket and whose end is engaged by the end wall of said socket when the actuating member moves in one direction, means for causing said variable-stroke member to come to rest prior to the completion of the return stroke of said actuating member, and means

for causing lubricating oil to flow into and out of said socket at each cycle of operations of the plunger-operating mechanism.

15. A variable feed pump provided with a fixed-stroke actuating member, a variable-stroke member, a connecting element for coupling said members together when the actuating member moves in one direction, a tripping device for said connecting element, an automatic adjusting mechanism for said tripping device comprising two parts, a spring that normally holds said parts in such a position with relation to each other that they move in unison, and means for compressing said spring so as to render one part inoperative with relation to the other.

16. A variable feed pump provided with a fixed-stroke actuating member, a variable-stroke member, a connecting element for coupling said members together when the actuating member moves in one direction, a tripping device for said connecting element, an automatic adjusting mechanism for said tripping device comprising two parts, one of which has a guide through which the other part passes freely, a stop on the part that passes through said guide, a resilient means that normally holds said stop in engagement with said guide, and means for enabling said stop to be moved away from said guide so as to render one part inoperative with relation to the other.

17. A variable feed pump provided with a fixed-stroke actuating member, a variable-stroke member, a connecting element for coupling said members together when the actuating member moves in one direction, a tripping device for said connecting element, an automatic adjusting mechanism for said tripping device comprising a rockable member provided with a guide, a rod that passes loosely through said guide, a stop on said rod that bears against one side of said guide, a spring on said rod interposed between the other side of said guide and a shoulder on said rod, and means for moving said rod so as to compress said spring and arrange the stop on the rod in an inoperative position with relation to the guide on said rockable member.

18. A variable feed pump provided with a plunger-operating mechanism that comprises a tripping device, a governor-controlled rock shaft, an arm loosely mounted on said rock shaft for actuating said tripping device, and a plurality of adjusting screws on said shaft that are adapted to engage shoulders on said arm and hold said arm rigid with respect to said rock shaft.

19. A variable feed pump provided with a plunger-operating mechanism that comprises a tripping device, a governor-controlled rock shaft, an arm loosely mounted on said rock shaft for actuating said tripping device, a plurality of adjusting screws

on said shaft that are adapted to engage shoulders on said arm and hold said arm rigid with respect to said rock shaft, a rockable element, a rod for transmitting movement from said rockable element to said rock shaft, and means for enabling said rod to be rendered inoperative with relation to said rockable element.

In testimony whereof I hereunto affix my signature in the presence of two witnesses, 10 this twenty-third day of July 1915.

HANS R. SETZ.
